UNITED STATES PATENT OFFICE

173,169

SLIPPER

Nell Moline Pfann, Great Neck, N. Y., assignor
 to I. B. Kleinert Rubber Company, New York,
 N. Y., a corporation of New York

Application April 26, 1952, Serial No. 19,487

Term of patent 14 years

(Cl. D7—7)

To all whom it may concern:

Be it known that I, Nell Moline Pfann, a citizen of the United States, residing at Great Neck, county of Nassau, and State of New York, have invented a new, original, and ornamental Design for a Slipper, of which the following is a specification, reference being had to the accompanying drawing, forming part thereof, wherein:

I claim:

The ornamental design for a slipper, as shown.
